DRILLABLE PACKER

O. L. Morriseett, Duncan, Okla., assignor to Halliburton Oil Well Cementing Company, Duncan, Okla.

Application April 15, 1947, Serial No. 741,630

2 Claims. (Cl. 166—12)

1

This invention relates to apparatus adapted for use in oil wells, and more particularly to a packer adapted to seal the lower end of a conduit such as a tubing within the casing of an oil well.

In the drilling or reworking of oil wells, it is often desirable to seal tubing or other pipe in the casing of the well. For example, when it is desired to pump cement or other slurry down tubing and force the slurry out into a formation, it becomes necessary to seal the tubing to the well casing and to prevent the fluid pressure of the cement slurry from lifting the tubing out of the well.

Packers, bridge plugs, and cement retainers, suitable for the general purposes outlined, are well known and the art is well developed. However, the devices heretofore designed have sometimes set prematurely while they were being lowered into the wells, or they have failed to hold properly against movement in the casing. Occasionally the packers of such tools have leaked or the back-pressure valves, with which they are usually provided, fail to seal properly. Even more serious than these difficulties, however, is the damage sometimes caused by inability to disconnect the tubing from the packer after the cementing operation is performed.

The apparatus of the present invention is designed to overcome these difficulties by providing a drillable packer which is set automatically by rotation of the tubing upon which it is run into the well and which is capable of being completely disconnected from the tubing before any cementing operation is performed. Provision is also made for holding a back-pressure valve open until the packer is set, so that the tubing fills with fluid while it is being run into the well. Yet when the packer is set, the holding means for the back-pressure valve is automatically released.

Accordingly, it is an object of the present invention to devise a drillable packer for use with tubing in oil wells which may be set to seal the tubing to casing merely by rotating the tubing, which has provision for readily disconnecting the tubing from the packer merely by pulling upwardly thereon, thus permitting a cementing operation to be performed after the tubing and the packer are disconnected.

It is another object of the invention to devise a novel means for controlling the setting of slips while simultaneously controlling the operation of a back-pressure valve associated with a drillable packer in a well.

2

Other objects and advantages reside in certain novel features of the arrangement and construction of parts as will be more apparent from the following description taken in connection with the accompanying drawing, in which:

Fig. 1 is a vertical cross-sectional view of a packer constructed in accordance with the principles of the present invention. The view shows the apparatus inside a casing but before it has been set in its operation position;

Fig. 2 is a vertical cross-sectional view of the packer shown in Fig. 1. This view shows the packer secured in position inside the casing, but before the packer has been disconnected from the tubing;

Fig. 3 is a vertical cross-sectional view of the apparatus of Fig. 2 but with the tubing disconnected from the packer;

Fig. 4 is a transverse cross-sectional view of the valve-holding means of the packer in Fig. 1, the section being taken along line 4—4 in Fig. 1;

Fig. 5 is a cross-sectional view of the latching means of the packer of Fig. 1, the section being taken along the line 5—5 of Fig. 1.

Referring to the drawing in detail, it will be seen that an oil well casing is illustrated at 11. Within this casing is a string of tubing, the lower end of which is shown at 12. To this tubing is attached a packer for temporarily sealing the tubing to casing 11.

The lower end of tubing 12 is attached by threads 13 to an upper mandrel 14. The mandrel 14 is provided with a "dizzy" thread 15, upon which is mounted a setting sleeve 16, which is provided with drag springs 17. The drag springs press against the casing 11 so that when the tubing 12 and mandrel 14 are rotated, the sleeve 16 is held against rotation but is forced to travel in a downward direction on the mandrel 14.

At the lower end of the sleeve 16, a trip ring 18 is mounted. With the parts in the "running-in" position shown in Fig. 1, the trip ring 18 is spaced some distance above the latching means which secures the packer to the mandrel 14. The latching means consists of an annular housing 20 which contains a release trigger 21 in the form of a split ring of spring steel. (See Fig. 5.) The lower end of this trigger ring 21 fits into a slot 21a in the lower mandrel 19 while the upper periphery is disposed beneath a shoulder at the upper rim of the housing 20. Thus the housing 20 cannot move either upwardly or downwardly on the mandrel 19 until the trip ring 18 on the sleeve 16 enters the housing 20 and expands the

trigger ring 21. After the trigger ring 21 is expanded, the housing 20 is free to slide on the lower mandrel 19.

A swivel or tube and ring coupling with shear pins is provided to rotatably connect the lower mandrel to the upper one. To this end, the lower mandrel 19 is provided at its upper end with a supporting ring 25 to which it is connected by means of shear pins 26. The supporting ring 25 and the shear pins 26 constitute the only means for connecting the lower mandrel 19 and the parts carried by it to the upper mandrel 14 and hence to the string of tubing 12. Thus the mandrels 14 and 19 may part upon the exertion of a predetermined stress on the shear pins. Threaded to the lower end of the upper mandrel 14 is a tube 22 which extends down into the lower mandrel 19. The tube 22 is provided with a shoulder 23 carrying hammer rings 24. The ring 25 is mounted on the tube 22 above the shoulder 23. The tube 22 can rotate inside the ring 25 and also can move longitudinally a limited distance inside said ring so as to impart a jar between the hammer rings 24 and the ring 25. Thus, the tube 22 may be used to hammer against the supporting ring 25 to shear pins 26 when the mandrel 14 is pulled upwardly after the slips are set.

The lower end of the tube 22 abuts against a seat 27 inside the mandrel 19, and the tube passes through packing 50 which is held in position inside the mandrel 19 by a nut 51. Thus until the mandrels 14 and 19 are separated following the shearing of pins 26, a seal is maintained between the tube 22 and the mandrel 19 and a leakproof fluid conduit is provided from the tubing 12 to the bottom of mandrel 19.

The mandrel 19 carries a set of upper slips 28 on an upper wedge member 29, and this wedge member carries a locking ring or pawl 30. A ratchet 31 is provided on the outside of the mandrel 19, and co-operates with the pawl 30 to prevent the upper wedge 29 from moving in an upward direction once it has moved down on the mandrel 19. Also carried on the outside of mandrel 19 is a packer 32, a lower wedge member 33, and a lower set of slips 34. The lower slips 34 are held in position by an interlocking bead 35 on mandrel 19 and by a clamping shear band 36. The lower wedge 33 abuts the shoe 32a of the packer which in turn is held against a shoulder 37 on the mandrel 19 and the upper wedge 29 abuts against the pawl 30 which in turn is held against a shoulder 38 on the mandrel 19. Thus, with the parts in the position shown in Fig. 1, the wedges and slips are prevented from moving upwardly on mandrel 19 when the apparatus is being lowered in a well.

The upper slips 28 are held in position by a clamping shear band 39 and by an interlocking bead 40 on the housing 20. Thus until the band 39 bursts, the upper slips 28 are secured to the housing 20.

The shear band 36 on the lower end of the mandrel 19 performs a double function. It holds the lower slips 34 locked in position on a bead 35 of coupling 44 secured to the mandrel 19 by threads 45 until the wedge 33 moves downwardly, and it holds a back-pressure valve open while the assembly is being lowered into the well. The back-pressure valve is shown at 41. It is of the conical type and is guided by a stem 42 which is carried by a spider section 43 (see Fig. 4) of the coupling 44. The valve 41 is urged upwardly by a spring 46 and is adapted to seat at 47. Horizontally slidable pins 48 (see Fig. 4) are pro-

vided for holding the valve open. The pins extend through slips 34, the spider section 43 and into a groove 49 provided in the valve stem 42. The pins 48 are held tightly in the groove 49 by the band 36 which presses against the heads of the pins. The holes 53 (see Fig. 4) in the slips 34, through which the pins 48 extend, are made smaller than the head of the pins but large enough to enable the pins 48 to be inserted easily. When the slips 34 are forced out to contact the casing, the band 36 bursts and the pins 48 are pulled out of groove 49 due to the outward radial movement of slips 34. This releases the back-pressure valve 41 and allows it to seat at 47.

The operation of the present invention in carrying out a cementing operation is as follows:

The apparatus is lowered into the casing 11, with the parts in the position as illustrated in Fig. 1. Upon reaching the desired depth the packer is set.

In order to set the packer, the tubing 12 is rotated in a clockwise direction. Since the drag springs 17 keep the sleeve 16 and the trip ring 18 from rotating, this causes the drag springs, sleeve, and trip ring assembly to be forced downwardly by the "dizzy" thread 15, on the mandrel 14. Only the tubing 12, the mandrel 14 and the tube 22 rotate. The mandrel 19 does not rotate since the tube 22 turns in the ring 25. The tubing must be rotated at least fifteen revolutions before the trip ring 18 contacts the trigger 21. This extra rotation is provided so that there will be no danger of the packer being set accidentally while it is going into the hole. With continued rotation the lower end of the trigger 21 is forced out of contact with the slot 21a releasing the housing 20. When the housing 20 is released, it, together with the upper slips 28, is forced downwardly on the mandrel 19 until the slips 28 contact the casing 11. With continued rotation of the tubing 12, the slips 28 will continue to move downwardly in the casing and thus move the lower wedge 33 downwardly and set the lower slips 34 and force the packer 32 out into sealing contact with casing 11. On the other hand, if the slips 28 do not slide down in the casing, the mandrel 14 is lifted, due to the jacking action of the "dizzy" threads 15 so that the mandrel 19 and all the parts carried by it are lifted up. In either case, the parts then assume the position shown in Fig. 2. It will be observed that, as the lower slips 34 are forced out by the wedge 33, the slips pull the pins 48 out of the groove 49 of the valve stem 42, thus releasing the back-pressure valve 41 and allowing it to seat at 47.

After the packer has been set the tubing may be released from the packer assembly by further rotation or by pulling up on the tubing with sufficient force to shear pins 26. These pins are made strong enough so that there will be no danger of them shearing until after the packer and slips have been set in the manner described above. Rather rugged shear pins must be employed because the forces employed in setting the slips and packing sleeve set up reactive forces which are transmitted through the shear pins 26. When the tubing has been released, it can then be lifted up until the tube 22 is clear of the packer assembly, as illustrated in Fig. 3. With the tubing released, circulation or reverse circulation of mud or other fluid can be carried out. If desired the tubing 12 can be set down again. The tube 22 will be guided by the taper in the top of nut 51 down through packing 50 and assume the posi-

tion inside the mandrel 19 like that shown in Fig. 2.

With the apparatus and its parts in the position shown in Fig. 2, either before or after the shearing of pins 26, a cementing operation can be performed. The cement slurry may be pumped down through the tubing, through the pre-set packer and out into the formation below. The slips 28 and 34 will prevent the packer from moving in either direction. The packer 32 will prevent slurry passing between the tube 22 and the mandrel 19. To insure that tube 22 will not be forced upwardly when a high fluid pressure is exerted, it is good practice to set part of the tubing weight down on the packer assembly.

After the cement has been pumped past the back-pressure valve 41 and the cementing operation has been completed, the pressure may be released and the tubing removed from the well. When the pressure is released the back-pressure valve 41 will close and the cement slurry will be held in place under pressure. There is no necessity for manipulation of the tubing as is usually required to disconnect it from the packer assembly. The shearing of pin 26, if this occurs before the cementing operation is started, (as preferable) disconnects the tubing from the packer, so that all that is required to remove the tubing from the well is merely to pull it in an upward direction. When the tubing 12 is brought out of the hole, the drag spring 17 and tripping ring 18 are brought out with it.

The present apparatus can be used as a bridge by dropping a bridging ball down through the tubing, with the ball seating at 27.

After the packer has performed its services and it is desired to remove it from the well bore, it may be drilled up. The wedge members 29 and 33, the mandrel 19, the trigger housing 20, and the coupling 44 may be made of some soft drillable material such as a magnesium alloy. The slips may be made of a more rugged drillable material such as cast iron.

Only one embodiment of the present invention has been shown and described herein, but it will be obvious to those skilled in the art that various other arrangements may be adopted without departing from the spirit of the invention and the scope of the annexed claims.

I claim:

1. A packer and setting assembly adapted to be connected to the lower end of tubing for sealing the same to casing in an oil well, said assembly consisting of an upper mandrel and a lower mandrel rotatably connected to each other through a tube and ring swivel coupling, and shear pins securing one of said coupling members to one of said mandrels, a packer slidably mounted on the outside of said lower mandrel adapted, when expanded, to engage the casing in the well to maintain a seal between said lower mandrel and the casing, two sets of slips and slip setting wedge members slidably mounted on the outside of said lower mandrel, one above and one below said packer, latching means on said lower mandrel for holding said slips and said packer in retracted

position while the assembly is being lowered into the well, said latching means including a release trigger latching the upper wedge member in inoperative position, a sleeve threaded to said upper mandrel, said sleeve having drag springs frictionally engaging a surrounding well casing to hold the sleeve against rotation as the upper mandrel is rotated, said sleeve having a trip ring adapted upon rotation of said upper mandrel to move in a longitudinal direction to engage and actuate said release trigger to release and expand the slips and packer and thereafter set said slips and packer, whereupon said upper mandrel may be disconnected from the lower mandrel merely by pulling upwardly on the tubing to shear said shear pins.

2. A packer and setting assembly adapted to be connected to the lower end of tubing for sealing the same to casing in an oil well, said assembly including an upper mandrel and a lower mandrel, a swivel connecting the two mandrels together, a shear device connecting an element of said swivel with one of said mandrels for permitting the same to part upon the exertion of a predetermined stress thereon, said lower mandrel having a packer, upper and lower slips and slip setting wedge members slidably mounted thereon together with latching mechanism for holding the same in inoperative position while the assembly is being lowered into the casing, said latching mechanism having a trigger initially locking said upper wedge member on said lower mandrel in an inoperative position and said upper mandrel having a tripping mechanism thereon for engaging and releasing said trigger to cause said latching mechanism to release said upper wedge member and packer and said slips and move the same downwardly on said lower mandrel until they are set in the casing, said tripping mechanism including a sleeve threaded to said upper mandrel and having drag springs for engaging the casing to hold the sleeve against rotation thereby causing movement of the sleeve longitudinally of the upper mandrel upon rotation of the upper mandrel, whereby the packer and slips may be set simply by rotation of the upper mandrel with respect to the lower mandrel after which the upper mandrel may be removed from the well simply by pulling upwardly thereon to shear said shear device or simply by further rotation of said upper mandrel to cause said tripping mechanism to exert a predetermined stress on said shear device by lifting the upper mandrel away from the set slips.
